UNITED STATES PATENT OFFICE

WILLIAM H. MILLSPAUGH, OF SANDUSKY, OHIO, ASSIGNOR TO PAPER & TEXTILE MACHINERY COMPANY, OF SANDUSKY, OHIO

GEARLESS SUCTION ROLL WITH EXTENDED SUCTION BOX

Application filed March 23, 1928. Serial No. 264,171.

The present invention relates to paper making machinery and more particularly to a suction roll gearless drive or means for driving or revolving the perforate shell of the roll by other than gears.

It has been common practice in recent years to drive the shell by direct intermeshing gears, one gear being rigidly fixed to the shell at or near one end, in any suitable or well known manner. Necessarily, this increased the over-all diameter by the difference between the exterior diameters of the shell and gear, making a larger and more cumbersome roll at that end. In the gear driven type there is a considerable loss of power through friction of the engaging gear teeth—roughly, 20% or more. In the gear driven type there are, obviously, at least two intermeshing gears between the in-drive shaft and the roll which it drives. Clearly, extra gears in the gear driven roll, as compared with the gearless drive, give added opportunities for repairs and other recognized disadvantages including the stoppage of the machine for the repairs to the gear drive.

The main objects of the present invention are to avoid this and other recognized difficulties met with in the gear driven roll.

In order to more clearly disclose the construction, operation, and use of the invention, reference should be had to the accompanying drawings forming part of the present application. Throughout the several figures of the drawings like reference characters designate the same parts in the several views.

In the drawings:

Fig. 1 is a central vertical longitudinal cross section through one preferred form of the invention.

Fig. 2 is a cross section on line 2—2 of Fig. 1 looking in the direction of the arrows.

Fig. 3 is a left hand end view of Fig. 1, with the drive omitted, and

Fig. 4 is a top plan view.

The type of gear driven suction roll in general use throughout the paper making industry, both in this country and abroad is pretty well disclosed in the re-issue patent of Mills- 45 paugh 13,100, dated April 12, 1910. For friction reduction or easier driving, roller bear-

ing mounting of the shell as in re-issue Mills- 50 paugh Patent 16,501 dated December 7, 1926, is used. For details as to mounting of the suction box within the shell and the anti friction roller support, reference is made to said 55 patents. The same is true as to the construction and arrangement of the suction box or chamber and its disposition within the shell, in general.

Referring to the drawings in detail, 1 indicates the perforated shell or roll through which the suction operates or is effective on the pulp, in the process of paper making. Within this shell is supported the suction box 2 of usual and well known construction. 60 Its longitudinal edges adjacent the inner face of the shell are provided with the usual well known packing strips, all as clearly shown in Re-issue Patent 13,100.

That end 2a of the suction box nearest the 65 drive is slidably mounted in a block or head 3. For this purpose the side walls 33a of the box near that end are grooved to slidably receive the co-operating edges of the side walls 40 of the head which define a U-shaped opening 41 in the head as more clearly shown in Fig. 3. In the head wall 42 at the bottom of said opening is disposed an annular plate or washer 4, to act as a spring seat for the coil suction box supporting spring 5. A stud or 70 pin 6 extends through and centers said spring 5, so that it will be kept in proper position. As will be readily understood, this spring, unless counteracted, would force the suction box 2 into tight frictional engagement with 75 the inner wall of the shell 1. To avoid this, set screws 43 are provided as in Re-issue Patent 13,100.

In the gear driven construction, in general use, the blocks or heads for supporting the 80 ends of the suction box are both carried by frames, brackets or other supports, entirely exterior to the shell. In the gearless drive of this invention that is not possible at the driven or drive end of the shell, as will be 85 evident.

The inner or drive end 44 of the shell has secured thereto a flanged ring 45 of greater diameter than said shell. The head or block 3 is mounted in said ring on a bearing 8, 100

having an inner race 8a positioned on said head and an outer race 9a positioned on said ring. A set of roller or other anti-friction bearings 9 are disposed between said races. 5 Both said ring 45 and the head 3 are suitably formed to provide seats 46 and 47 for said races.

At the opposite or front end 10a, the suction box is supported entirely exterior of the shell 1. At this end the shell 1 is provided with a head 10 having an outwardly extended reduced hollow journal 11 which revolves freely on roller or other anti friction bearings 12 located in a suitable bearing cage 13 mounted in a frame or housing 14 of the standard 15. Said journal 11 and bearing 12 is particularly desirable for high speed rotation of the heavier shells, as met with in the machines in which these rolls are used. In 15 order to apply a suction at this end of the shell a tubular section 16 extends from the front end 16a of the suction box through said hollow journal 11, concentrically therewith and spaced therefrom, as clearly shown 20 in Fig. 1.

The suction box is supported at this end by a head 3a having a circular aperture 48 therethrough for receiving said tubular extension 16. Said head 3a is formed about said aperture with an outwardly extending flange 17 which provides a relatively large supporting surface for said extension. Said flange 17 is keyed or otherwise securely fastened to said extension 16 so as to turn therewith.

Said head 3a is mounted for sliding movement on a disc or plate 19 by means of guides or ways 18 which receive the side edges 18a of said head. The disc or plate 19 is in turn detachably secured on the housing 14 by 40 means of bolts 22 which extend through arcuate slots 23 in said plate and are threaded into said housing 14.

The mounting of said head 3a on said disc or plate 19 is adjusted by means of a coil spring 5a, similar to spring 5, extends to move said head radially of said plate. Said spring 5a is centered by a headed pin 6a, the head 50 of which is seated on a relatively wide flange 21 located adjacent the periphery of said plate 19. Said spring 5a bears at one end against said head 50 and at its opposite end against a movable block 4a which has an aperture 52 for receiving the shank 53 of said pin 6a. Said block 4a rests against the outer 55 side of the flange 17 to thereby transmit the force of said spring to the head 3a and extension 16.

The compression of spring 5a is regulated by means of a set screw 54 which is threaded 60 through a lug 20 on the plate 19 opposite the flange 21. The inner end of said set screw contacts a flange 55 formed on the head 3a beneath said lug 20 to thus resist the force of said spring 5a.

65 This construction permits of angular ad-

justment of the suction box by merely loosening the bolts 22 and rotating the disc or plate 19 the desired degree. Since the suction box extension 16 is keyed to the head flange 17 and said head 3a is secured to rotate with the 70 plate 19, it is apparent that rotation of said plate 19 rotates said suction box.

It is hardly necessary to state that the housing 14 is in section to provide for ready removal of the upper part of the same and thus 75 permit the forming wire of the machine to be readily removed and replaced.

The usual elbow connection 60 is provided for the reduced end of the suction box. It may be made detachable in any of the usual 80 and well known ways, as by a notched collar, flange and co-operating eye bolts, or the like.

At the drive end 44 a disc or circular head 24 is provided as the driving connection. Said disc has a peripheral flange 25 which is 85 securely fixed to the flange of ring 45 in any suitable and well known manner. From the center of the disc extends the indrive shaft 26 which may be driven direct from a motor or any usual driving machinery (not shown). 90

It is obvious, likewise, that it may be driven indirectly through a clutch or similar connection. At a point near the disc or driving head 24 the shaft 26 is journaled in suitable 95 antifriction bearings 27 positioned in the standard 28. The member or element which immediately connects the shell to the drive shaft has been shown and described as a flanged disc or plate 24 and as fixed to the shell. Clearly, this disc may be cut away 100

to practically any desired extent as until only a fork of two opposite arms remains, the free ends of these arms being secured to the ring 45 in the same manner as stated for the disc flange. Of course, any other number of arms 105 may similarly be provided. The disc construction described is a strong, efficient, compact, economical form and one readily and quickly made. In some cases, especially with small diameter rolls it may be preferable to 110 have a detachable instead of a fixed connection. This may be done in many ways as by pins or studs on the shell cooperating with a key hole in the disc or bayonet or other locking slots in the flange or in the arm ends; or 115 the flange or arm ends may be simply bolt-and-nut connected.

It is the intention, of course, to include in this application and to cover by the appended 120 claims both the fixed and detachable connections.

A readily accessible deckle adjustment indicated generally by the numeral 30a is provided at the front end 10a of the machine and is made as compact as practicable to adapt it 125 to the least possible space. In the preferred form two separate and independent shafts 30 and 31 are employed, each shaft being threaded into and through a deckle block or head 31a. Said heads 31a are longitudinally 130

slidable between the side walls of the suction box and the top wall thereof and the adjacent shell surface and in simultaneous contact with all four surfaces as clearly shown in Fig. 1. The shaft 30 is tubular and threaded through the deckle head 31a nearest the suction end 10a and is journaled in the shell box supporting head 3a at that end. Shaft 31, on the other hand, preferably, is solid, and extends through and is journaled in the shaft 30. This shaft is threaded into the opposite deckle head. Each shaft, of course, is provided with a hand wheel, crank, or any other suitable means 32 for operating the same. Said shafts are oppositely threaded to cause the deckle blocks 31a to travel inwardly from the shell ends toward the center. This makes a simple, efficient, and compact construction whereby either deckle may be adjusted to any extent desired without in any degree affecting the other, while at the same time occupying only the space required for the single adjusting means for one deckle head.

25 It will be clear on reference to Fig. 1 that there are three sets of bearings, all together, and that all three sets are very easily and quickly accessible at all times. In case of damage, with resulting need of repair or replacement, this is very important and results in a big saving in time in making the repairs, as well as the saving of the heavy loss in the operation and production of the machine during the time it is idle for repairs.

35 It is obvious that changes may be made in the construction, operation, and disposition of various parts of the machine, within the scope of the appended claims, without in any sense departing from the field of the invention, and it is intended to include all such within this application, wherein only a single form has been disclosed, as illustrative of the invention, merely.

What I claim is:

45 1. In a suction roll, a revolvable shell, a relatively non-revolvable suction box within said shell, stationary heads supporting opposite ends of said suction box exterior to said shell, means extending about one of said heads for driving said shell, a tubular journal of reduced diameter extending from the opposite end of the aforesaid shell, and a suction connection of reduced diameter carried by said box and extending through said journal in spaced relation thereto and mounted in the adjacent stationary head.

2. In a suction roll, a revolvable shell, a relatively non-revolvable floating suction box within said shell, stationary heads supporting opposite ends of said suction box exterior to said shell, means extending about one of said heads for driving said shell, a tubular journal of reduced diameter extending from the opposite end of the aforesaid shell, and a suction connection of reduced diameter car-

ried by said box and extending through said journal in spaced relation thereto and mounted in the adjacent stationary head.

3. In a suction roll, a perforate shell, a suction box in said shell, a head supported from one end of said shell exterior to said shell forming a journal for said shell end, one end of said suction box being supported loosely in said head for radial movement therein, a second stationary head beyond the opposite end of the shell and a tubular member extending from said suction box and received in said second head for supporting the opposite end of said suction box for radial movement of the same.

4. A structure for mounting a suction box in a suction roll comprising a stationary head supported from one end of said roll exterior to the same and about which said roll end revolves, said head having an opening therein for receiving and supporting said head for radial movement therein, a support for rotatably mounting the opposite end of said roll, a tubular member extending from said suction box to a point beyond said support and a second head independent of said roll detachably secured to said support and encircling said tubular member for supporting the same.

5. A device for mounting a suction box in a suction roll comprising a head supported from one end of said roll and about which said roll revolves, said head having an opening therein, one end of said suction box being supported in said opening for radial movement therein, a second head beyond the opposite end of said roll having an opening therein, a tubular member extending from said suction box into said opening wherein it is supported, means for supporting said second head for rotation relative to said roll and means for providing radial movement of said second head with respect to said roll end.

6. A supporting structure for mounting a suction box in a suction roll comprising a ring on one end of said roll, a head exterior of said roll in said ring forming a journal for one end of said roll, said head having an opening for receiving and supporting one end of said suction box, a tubular member extending from the other end of said suction box beyond the adjacent roll end, a second head having an aperture therein for receiving and supporting said tubular member, a support for said second head and means for slidably mounting said second head on said support.

7. In a suction roll having a suction box therein, a supporting device for said suction box comprising a ring on one end of said roll, a head in said ring having an opening for receiving and supporting one end of said suction box, means between said head and ring providing for rotation of said roll about said head, a tubular member on the opposite

end of said suction box extending beyond said roll, a standard for rotatably mounting said roll, a disc detachably secured to said standard, a head slidably mounted on said disc, said disc and head having aligned openings to receive and support said tubular member, resilient means for varying the position of said head on said disc, said head being keyed to said tubular member whereby rotation of said disc causes rotation of said tubular member.

8. A device for rotatably supporting a suction box in a suction roll, comprising a head supported from one end of said roll exterior thereto and providing a journal about which said roll revolves, said head having an opening therein for receiving and supporting one end of said suction box, a disc beyond the opposite end of said roll, a support for said disc, a second head slidably mounted on said disc, said disc and head having aligned openings therein, a tubular member extending from the other end of said suction box through the openings in said disc and head, a wide flange about the opening in said head for supporting said tubular member, said flange being keyed to said tubular member, means for varying the radial position of said head on said disc and means for detachably securing said disc to its support to provide for rotation of said disc and accordingly said suction box relative to said roll.

9. A support for the driven end of a suction roll having a suction box therein, comprising a hollow trunnion on said roll end, a pedestal for supporting said trunnion, bearings between said trunnion and pedestal, a tubular member extending from said suction box through said trunnion in spaced relation thereto, a disc detachably secured to said pedestal beyond the end of said trunnion, a head slidably mounted on said disc, said head and disc having openings through which said tubular member extends, a flange about the opening in said head for supporting said extension, means for radially sliding said head relative to said disc and means providing for angular movement of said head, disc and extension relative to said roll end.

10. A suction roll comprising a perforate shell, a suction box in said shell, a ring secured to one end of said shell, a stationary head in said ring having an opening therein for receiving one end of said suction box to support said end, a bearing between said head and ring providing for rotation of said shell about said head, a hollow extended trunnion on the opposite end of said shell, means for rotatably supporting said trunnion, a tubular member extending from said suction box through said trunnion in spaced relation thereto, a centrally apertured disk detachably secured to said trunnion supporting means, a head slidably mounted on said

disc and having a flanged opening in alignment with said disc opening for receiving and supporting said tubular member and resilient means for varying the position of said head on said disc.

In testimony whereof I affix my signature.
